(57) **CLAIM**

The ornamental design for a display screen or portion thereof with a heatmap of maximum concurrent users for period split by hour, as shown and described.

DESCRIPTION

The FIGURE is a view of a display screen or portion thereof with a heatmap of maximum concurrent users for period split by hour.

The outermost broken lines show the display screen or portion thereof and form no part of the claimed design. The broken lines within the figures show portions of the graphical user interface that form no part of the claimed design. Although the broken lines may include various styles or thickness, no broken lines form part of the claimed design.
